UNITED STATES PATENT OFFICE.

SAMUEL T. PRATT, OF NANTICOKE, PENNSYLVANIA, ASSIGNOR OF ONE-FOURTH TO MICHAEL J. McDONALD AND ONE-FOURTH TO ANTHONY V. McDONALD, BOTH OF NANTICOKE, PENNSYLVANIA.

MINER'S TICKET BOX.

Application filed May 16, 1923. Serial No. 639,351.

To all whom it may concern:

Be it known that I, SAMUEL T. PRATT, a citizen of the United States, residing at Nanticoke, in the county of Luzerne and State of Pennsylvania, have invented certain new and useful Improvements in Miners' Ticket Boxes, of which the following is a specification, reference being had to the accompanying drawings.

10 This invention relates to devices for holding miners' checks on coal cars.

It is the practice in coal mining plants for the coal miners after they have filled a car to hang thereon or otherwise attach thereto a check, each man having a certain number, and the checks used by each miner having that number so that the weigher at the tipple may identify the car as having been filled by one certain miner. These 15 checks or tickets are very liable to become detached from the car, and it is also the case that a dishonest miner will remove the proper check from the car and place his own check thereon so that the real miner of the 20 coal is not credited therewith and the dishonest miner is.

25 The general object of my invention is to provide a check holder of such character that a check may be readily inserted within the holder and will be prevented from detachment until the car has reached the tipple and tipped to a discharging angle, at which time the check may be readily removed by the weigher.

30 A further object is to provide a device of this kind which is so constructed that the check may be readily seen at any time when desired to be inspected. This is an indispensable feature of a construction of this 35 character.

40 Another object is to provide a device of this character including two chambers having two slides therein, one of these slides being adapted to receive the check. Once 45 the check has dropped into the slide it passes into the other slide and cannot be removed from this slide until the car and the holder mounted thereon are turned to a tipping angle. Then and not until then the check 50 will run to the first named slide and may be removed from the holder by opening the slide. The first named slide is provided so that the check may be inspected whenever necessary by simply opening the slide.

The opening of the slide permits the check 55 to be inspected but will not permit the check to be removed from the holder.

Other objects will appear in the course of the following description.

My invention is illustrated in the accompanying drawings, wherein:—

Figure 1 is an elevation of a miner's ticket box constructed in accordance with my invention with one wall removed, one of the slides being partly in section; 65

Figure 2 is a like view to Figure 1, but showing the slide 21 pulled out;

Figure 3 is a section on the line 3—3 of Figure 1;

Figure 4 is a like view to Figures 1 and 70 2 but showing the operation of the device when the box is tilted, the slide 15 being partly broken away;

Figure 5 is a side elevation of a miner's car with my invention applied thereto. 75

Referring to these drawings, it will be seen that the holder is formed in sections A and B. These sections are alike in all respects and are held to each other by rivets, bolts or any other suitable attaching means. 80 The sections when placed together are formed to provide two chambers 10 and 11 divided from each other by a transverse partition 12. This partition 12 formed by the abutting faces of the two sections has 85 a passage 13 leading from the chamber 11 into the chamber 12, this passage having its upper and lower ends disposed at an inclination upward and toward the chamber 10. The chamber 10 is reduced in width adjacent its upper end so as to provide two opposed shoulders 14, and operating within this chamber 10 is a slide 15, this slide having a thickness equal to the depth of the 90 chamber 10.

The lower end 16 of the slide has a width equal to the width of the chamber between its opposed walls but above this portion 10 the slide is reduced in width so as to provide shoulders or stops which are adapted to 100 abut against the stops 14 and thereby limit the outward movement of the slide. At its upper end the slide is provided with a head 18 which is larger in area than the area of the open end of the chamber 10 so that thus 105 the slide is limited in its inward movement and limited in its outward movement by the shoulders 17. The slide is formed interme-

diate its ends with a slot 19 at approximately the middle of the slide, the upper end of this slot being downwardly inclined and away from the wall 12, while the lower end 5 of the slot is upwardly inclined and away from the wall 12. The slot is cut away at 20 and the faces of the slot adjacent this cut-away portion are slightly rounded off or thinned.

10 Disposed within the chamber 11 is a slide 21. The upper end of this chamber is formed with the inwardly extending shoulders 22 and 23 and the slide at its lower end 24 has a width equal to the extreme 15 width of the chamber 11 and then is reduced in width so as to provide shoulders 25, these shoulders being adapted to engage with the shoulders 22 and 23 to limit the outward movement of the slide. The upper end of 20 the slide is formed with the enlarged head 26 which, of course, is larger in area than the cross sectional area of the chamber 11 so that this head limits the inward movement 25 of the slide as well as forms a handle whereby the slide may be operated. This slide is formed with a slot 27. The bottom of this slot extends straight inward from that portion of the slot nearest the opening 13 and on a level with the lower end of this 30 opening and then extends upward, as at 28. The upper end of the slot is curved downward and away from the partition 12, as at 29. Thus it will be seen that the opening 30 of the slot is less in height than that 35 portion of the slot which aligns with the passage 13. The side walls of the slide which define this slot are cut away to provide approximately elliptical openings 31.

Coacting with the holder is the check 40 illustrated in Figure 2. This is a round metal disk designated 32 and is provided on opposite faces and at diametrically opposite portions with a number which identifies the miner to whom the check belongs and who 45 has mined certain coal.

In the use of this device, the holder is attached to the car, as illustrated in Figure 5, and after the miner has filled the car, with coal he pulls out the slide 15 which, 50 when pulled out, permits the check to be introduced at the cut-away portion 20. The check is held within the slot 19 by the end walls of the chamber 10 until the slide is fully pushed in. When the slide is fully 55 pushed in, the check will roll down the inclined bottom of the slot 19 and roll down the inclined bottom of the passage 13 and onto the bottom of the slot 27. When it is in place within the slot 27 it cannot roll 60 back up these inclined faces and must remain within the slide 21. If it is desired to inspect this check, then the slide 21 may be pulled outward, carrying the check with it. When the slide is pulled 65 outward, as illustrated in Figure 2, the slots

31 are disposed beyond the walls of the chamber 11 and, therefore, the number on the check may be readily seen. Preferably, as before remarked, the numbers are disposed on opposite faces of the check in diametrically opposite positions so that no matter where the check is disposed the number will be observable through the openings 31. Furthermore, when the slide 21 is fully retracted, the check 32 may be shifted by hand 75 until the number is observable.

Under ordinary circumstances the chambers 10 and 11 are vertical and, therefore, once the check is deposited and passed into the slide 21 it cannot be removed, but when 80 the car is carried to the tipple and is tipped, as a consequence the check will roll from the slot 27 through the passage 13 into the slot 19 and under these circumstances when this slide 15 is pulled out the check will come 85 with it and may be readily removed by the weigher.

It will be seen that with this device two checks cannot be deposited in the slot 27 at the same time and if a second check is deposited it will remain in the slide 15. This device is very simple, can be readily applied, and is certain in its action. Of course, it is obvious that the slot 27 might be made large enough to hold two checks 95 if desired as, for instance, where there is a check for the miner and also a check for an operator working with him. Of course these checks under those circumstances would be differently numbered or otherwise 100 marked.

I claim:—

1. A check holder for mine cars comprising a body formed to provide two chambers and a check passage connecting the chambers, a shiftable carrier mounted in each chamber and partly withdrawable from the chamber, each carrier having a check slot, one of the carriers being withdrawable to an extent permitting the insertion or removal 105 of the check from the slot and the other carrier being prevented from being withdrawn to an extent which will permit the removal of the check therefrom, the last named carrier having an observation opening whereby 110 the check may be observed.

2. A check holder for mine cars comprising a body formed to provide two chambers, a carrier shiftable mounted in each chamber and partly withdrawable from the chamber, each carrier having a check receiving slot, one of the carriers being withdrawable to an extent permitting the insertion or removal 115 of the check from the slot, means preventing the other carrier from being withdrawn to an extent which will permit the removal of the check, the last named carrier having the lower end of its slot disposed below the level of the first named carrier and there being a passage between the two chambers 120 125 130

bers permitting the check to pass from the slot of the first named carrier to the slot of the second named carrier when the carriers are disposed in a horizontal plane, the passage permitting the check, however, to pass from the second named carrier to the first named carrier when the body is inclined from a horizontal plane, the second named carrier having an observation opening in its

10 side.

3. A check holder for mine cars comprising a body formed to provide two parallel chambers, a check slide in each chamber and partly withdrawable from the chamber, each slide having a check receiving slot, one of the slides being withdrawable to an extent permitting the insertion or removal of the check into or from the slot, means preventing the other slide from being withdrawn to an extent which will permit the removal or insertion of a check into the slot, there being a passage connecting the two chambers permitting the check to roll from the slot of the first named slide into the slot of the second named slide and the bottom of the slot of the second named slide being below the bottom of the slot of the first named slide, the second named slide having observation openings in its side whereby the check may be observed.

4. A check holder for mine cars comprising a body formed to provide two aligned chambers, a check slide mounted in each chamber and partly withdrawable from the chamber, each slide having a check slot extending into the slide from one edge, one of the slides being withdrawable to an extent permitting the insertion or removal of the check into or from the slot and the bottom of this slot being downwardly and laterally inclined toward the other chamber, the other slide having means preventing its withdrawal from the chamber to an extent which will permit the insertion or removal of a check therefrom and having the bottom of its slot disposed below the bottom of the first named slide and the side wall of the slot having an observation opening; there being a passage leading from one chamber to the other and the bottom of said passage at one end being on a level with the lower end of the slot of the first named slide and on its other end being on a level with the bottom

of the slot of the second named slide whereby to permit the passage of the check from the first named slide to the second named slide. 55

5. A check holder for mine cars comprising a relatively thin body having two parallel chambers separated by a partition, the partition having a downwardly and laterally inclined slot leading from one chamber to the other, each of said chambers being formed with inwardly projecting shoulders, reciprocatable slides mounted in each chamber, each slide having a slot extending from edge to edge of the slide, each slide being provided with shoulders coacting with the first named shoulders to limit the movement of the slides, one of said slides being movable out of the chamber to an extent to permit the insertion or removal of a check from said slot, the other of said slides having shoulders preventing the movement of the slide out of its corresponding chamber to an extent which will permit the insertion or withdrawal of a check, the lower end of the first named slide being downwardly inclined and normally on a level with the lower end of the passage through the partition, the lower end of the second named slide being below the lower end of the first named slide, 80 the second named slide having side walls provided with observation openings through which the check may be observed when the slide is withdrawn from the chamber.

6. A check holder for mine cars comprising a body adapted to be attached to a car and formed to provide two chambers, means whereby a check may be disposed in one chamber and caused to pass into the other chamber, means preventing the return of the check from the second named chamber to the first named chamber while the body is in a horizontal position but permitting the return of the check when the body is canted in one direction, means in the first named chamber whereby a check disposed therein may be withdrawn, and means in the first named chamber whereby a check disposed therein may be partially withdrawn to observe the check, said means preventing the full withdrawal of the check from the chamber. 95 100

In testimony whereof I hereunto affix my signature.

SAMUEL T. PRATT.
